UNITED STATES PATENT OFFICE

THEODOR BRAGARD, OF HAMBURG, GERMANY, ASSIGNOR TO THE FIRM OF MACAO-WALZENMUKLEN-GESELLSCHAFT MIT BESCHRANKTER HAFTUNG, OF HAMBURG, GERMANY

GRINDING MILL

Application filed July 3, 1928, Serial No. 290,115, and in Germany June 9, 1927.

This invention relates in the first place to a grinding device in which the end faces of several planetarily driven grinding discs co-operate with an annular grinding disc located 5 within a casing, and in the second place to a mill in which the planetarily rotatable grinding discs are rigidly connected with rolls performing planetary rotation around a central shaft, said rolls belonging to a roller mill, 10 known per se, fitted in the same casing. The combined mill in which the goods are preferably first fed to the set of rolls and are expelled by the pressure of the latter directly to the set of grinding discs is particularly 15 adapted for the treatment of plastic masses, such as paints, which can be ground to the finest sizes. Preferably all the grinding bodies are formed of hard porcelain and all the metallic parts which contact with the goods 20 are enamelled.

In the accompanying drawing is illustrated by way of example a construction according to the invention.

Fig. 1 is a vertical longitudinal section 25 through the combined mill. Fig. 2 shows a modified form of feeding device. Fig. 3 is a section of the line A—A of Fig. 1 viewed from the left and shows the rotatable grinding discs in one position. Fig. 4 is a section 30 on the line A—A of Fig. 1 showing the grinding discs in a position of 180° displaced from the position of Fig. 3. Fig. 5 is a section on the line A—A of Fig. 1 viewed from the right. Fig. 6 is a section on the line B—B 35 of Fig. 1 viewed from the left. Fig. 7 is a section on the line B—B of Fig. 1 viewed from the right.

As shown in the drawing, the invention is incorporated in a mill including a central 40 roll 1 and rolls 2 performing planetary rotation around the roll 1, it being understood, that the rolls 1 and 2 are preferably conical as shown. The central roll is driven by means of the shaft 3 and the belt-pulley 4 mounted 45 on said shaft. The central roll 1 is provided at its ends with spur gears 5 meshing with spur gears 6 on the ends of the rolls 2. The gears 6 mesh with circular racks 7 in the casing. The rolls 1 and 2 preferably consist of 50 hard porcelain and the casing 8 is provided

with a lining 9 which if the rolls 1 and 2 are conical is also conical and also consists of hard porcelain.

The goods are fed to the rolls 1 and 2 by 55 way of a hopper 10 and a worm 11, the axis of which may be disposed vertically as shown in Fig. 1 or may, as shown in Fig. 2, be coincident with the shaft 3. A conical valve 12 which is vertically adjustable by actuation 60 of a hand wheel 14 controlling the lever 13 regulates the delivery of the goods from the hopper 10 to the worm 11.

On the outer faces of the left-hand gears 6 are eccentrically mounted grinding discs 15 the end faces of which co-operate with a stationary annular grinding disc 16 having a close fit within the casing. The discs 15 depart from circular form, being in the present case of elliptical form.

The eccentricity and dimensions of the 70 discs 15 which rotate with the gears 6 are such that the said discs 15 in their rotary motion alternately sweep past the point of engagement of the gears 6 with the gear 5 and the points of engagement of the gears 6 with the circular rack 7. The faces of the discs 15 adjacent to the gears 6 are formed with grooves 17 at the points of maximum eccentricity, the mean distance of which 75 grooves from the axes of rotation of the discs 15 corresponds about to the radius of the pitch circle of the spur gears 6 and which grooves communicate with holes 18 leading to the outer faces of the discs 15. It is thus ensured that the goods pressed by the rolls 80 1, 2 through the points of engagement of the gears 6 with the gear 5 and the circular rack 7 will not exercise a binding or choking action at the points where the grinding discs 15 sweep past said points of engagement, but can pass through the holes 18 to the outer grinding and rubbing faces of the discs 15. The stationary annulus 16 is provided as shown in Figs. 5 and 6 with tangential grooves 85 30 on each side, and its end face which is to the left in Fig. 1 contacts with an additional movable grinding annulus 19 which is fixed to the shaft 3 by means of a boss 20 so as to be longitudinally movable along the shaft 3 but rotatable with the 90

95 100

shaft 3. The stationary annulus 16 is provided on the face which is at the left in Fig. 1 with a pocket-like cavity 21 which is found advantageous for effecting good distribution of the goods on the grinding faces between 16 and 19. This pocket 21 is somewhat displaced from the vertical in the direction of rotation of the disc 19.

By axial shift of the shaft 3 it is possible to adjust the intervals between the central roll 1 and the rolls 2. The shaft 3 is provided at the right-hand end with a through-slot *a* and abuts through the intermediary of a collar *c* against a powerful helical spring 22, the compression of which is adjustable by operation of a set screw 23. A cotter *b* penetrating the slot limits the shift of the shaft 3 towards the right, it being understood that Fig. 1 shows the rolls spaced at their furthest distance apart, that is, the extreme right-hand position of the central roll. Engaging the left-hand end of the shaft 3 is a set-screw 24. To reduce the spacing of the rolls, the shaft 3 can be shifted to the left by operation of the set-screws 23 and 24. With this displacement the base of the slot *a* is spaced from the cotter *b*, and the shaft 3 is then subject only to the action of the spring 22. The central roll 1 is thus resiliently movable in axial direction which is desirable for compensating for unforeseen resistance. Also the pressure of the rotatable disc 19 against the stationary disc 16 is adjustable. To effect such adjustment there is provided a screw-threaded bush 25 which bears, preferably through the intermediary of a ball-bearing 26, against the boss 20, and by adjustment of which bush the boss together with the disc 12 can be shifted axially. If the disc 16 is so guided in the casing that it can shift in the longitudinal direction of the latter but cannot rotate, then by adjustment of the screw-threaded bush 25 also the pressure between the disc 16 and the discs 15 can be varied. The discharge of the ground goods is effected at 27. In front of the rolls 1 and 2 is a distributing chamber 28 to which the goods are fed by the worm 11. Due to the peculiar movement of the planetarily rotatable elliptical grinding discs 15 there is effected a pumping action which continuously pumps forward the mass which has attained in the roll mill a sufficient fineness to pass between the discs and which presses the goods through the grinding discs located at the end of the mill. The entire grinding operation is effected positively from the feed worm up to the point of discharge. The elliptical discs 15 are provided on their end faces with crossing grooves 31 (Figs. 3 and 4) so that the sucking effect of these discs varies continuously and their surfaces wear and act uniformly.

In the position shown in Fig. 3 the sucking action is effected with regard to the upper

discs on their right-hand side, while in the position shown in Fig. 4, in which the limit of the throw is towards the centre, the sucking action is effected on the other side.

The set of grinding discs may be added to if desired by incorporating additional grinding discs as shown in Figs. 6 and 7.

I claim:—

1. A grinding mill incorporating a casing, an annular grinding disc located in said casing, a plurality of planetarily driven grinding discs the end faces of which co-operate with said annular disc, grinding rolls connected with said planetarily driven grinding discs and a central roll about which the first named rolls rotate and which is externally driven, intermeshing spur gears on the rolls to planetarily drive the outer rolls from the central roll, the end faces of the spur gears at the exit ends of the planetary rolls carrying the movable discs. 75 80 85

2. A grinding mill incorporating a casing, an annular grinding disc located in said casing, a plurality of planetarily driven grinding discs the end faces of which co-operate with said annular disc, grinding rolls connected with said planetarily driven grinding discs and a central roll about which the first named rolls rotate, and which is externally driven, intermeshing spur gears on the rolls to planetarily drive the outer rolls from the central roll, the end faces of the spur gears at the exit ends of the planetary rolls carrying the movable discs, the movable discs being elliptical and of such dimensions or of such eccentricity that they alternately sweep past the points of engagement of the spur gears on the planetary rolls with the spur gear on the central roll, and the points of engagement of the first mentioned gears with a circular rack within the casing. 90 95 100 105

3. A mill such as claimed in claim 1, further characterized in that the faces of the movable discs adjacent to the spur gears are provided at the points of maximum eccentricity with grooves the mean distance of which from the axes of rotation of the said discs is equal to about the radius of the pitch circle of the spur gears and which communicate with holes leading to the outer faces of the discs. 110 115

4. In a grinding mill, a casing, a stationary grinding disk in said casing, other grinding disks mounted in said casing and of elliptical form and being facially presented to the adjacent face of the stationary grinding disk to coact therewith to grind material delivered between the faces of the disks, and means for imparting planetary motion to the elliptical grinding disks. 120 125

5. In a grinding mill, a casing, a conical grinding roll rotatably mounted therein, an annular grinding disk within the casing concentric to the axis of rotation of said roll, a plurality of grinding disks mounted in the 130

casing adjacent the ends of conical grinding rolls, and of elliptical form and presented facially to the adjacent face of the first mentioned disc, and adapted to cooperate with said first-mentioned disc, conical grinding rolls rotatable within the second mentioned grinding disks and about the first mentioned roll, and means for imparting rotary motion to the first and second mentioned grinding rolls and to the said elliptical grinding disks.

6. In a grinding mill, a casing, a conical grinding roll rotatably mounted therein, an annular grinding disk within the casing concentric to the axis of rotation of said roll, a plurality of grinding disks mounted in the casing and of elliptical form and presented facially to the adjacent face of the first mentioned disks and cooperating therewith, conical grinding rolls rotatable with the second mentioned disks and about the first-mentioned roll, and cooperable therewith, and on the ends of which said plurality of grinding disks are mounted means for imparting motion to the first and second mentioned grinding rolls and to the said elliptical grinding disks, means within the casing for feeding the material to be ground, to the rolls, at the ends thereof remote from the said grinding disks, and means for delivering the ground material from the casing as delivered from said disks.

7. In a grinding mill, a casing, a conical grinding roll rotatably mounted therein, an annular grinding disk within the casing concentric to the axis of rotation of said roll, a plurality of grinding disks mounted in the casing and of elliptical form and presented facially to the adjacent face of the first mentioned disk and cooperating therewith, conical grinding rolls rotatable with the second mentioned grinding disks and about the first mentioned roll and cooperable therewith, the said plurality of disks being mounted adjacent the ends of said conical grinding rolls, a grinding disk rotatable with the first mentioned grinding roll and coacting, facially, with the other face of the annular grinding disk, and means for imparting rotary motion to the first and second mentioned grinding rolls and to the said elliptical grinding disks.

In testimony whereof I have signed my name to this specification.

THEODOR BRAGARD.
